UNITED STATES PATENT OFFICE.

JASON McGREGOR CHANDLER, OF MEXIA, TEXAS.

FLUID-VENDING MACHINE.

1,198,890.

Specification of Letters Patent. Patented Sept. 19, 1916.

Application filed December 28, 1915. Serial No. 69,032.

To all whom it may concern:

Be it known that I, JASON M. CHANDLER, a citizen of the United States, and a resident of Mexia, in the county of Limestone and State of Texas, have invented a new and Improved Fluid-Vending Machine, of which the following is a full, clear, and exact description.

My invention has for its object to provide a fluid vending machine which may be used for vending gasolene and other liquids, the machine being so constructed that it may be regulated to dispense more or less gasolene as desired upon the insertion in a coin slot of a coin of a predetermined denomination. In this way, the quantity of gasolene dispensed on the operation of the machine may be changed to agree with the current price of gasolene.

Another object of the invention is to provide a plurality of coin slots for coins of various denominations, and apparatus for dispensing gasolene in large or small quantities, depending upon the particular coin which is inserted before the machine is operated. The regulating means, to change the quantity of gasolene delivered, with the change in the price of gasolene, are so constructed that when operated, they will change the quantity delivered when the machine is operated on the insertion of a coin in any of the said coin slots, the quantity delivered being regulated by the said means with reference to the price of gasolene and the coin slot in which the coin is inserted before the machine is operated.

Another object of the invention is to provide coin-actuated means for moving the parts of the machine into operative position.

Additional objects of the invention will appear in the following specification, in which the preferred form of my invention is described.

Reference is had to the accompanying drawings, in which similar reference characters denote similar parts in all the views, in which—

Figure 1 is a front elevation of my invention; Fig. 2 is a side elevation of Fig. 1; Fig. 3 is a sectional view on the line 3—3 of Fig. 2; Fig. 4 is a sectional view on the line 4—4 of Fig. 1; Fig. 5 is a sectional view on the line 5—5 of Fig. 3; Fig. 6 is a sectional view on the line 6—6 of Fig. 3; Figs. 7, 8 and 9 are enlarged fragmentary views showing the coin-actuating means in

different positions; and Fig. 10 is a fragmentary perspective view showing the position of the trigger.

By referring to the drawings, it will be seen that a casing 11 is provided having a base 12, a frame 13 being supported on the base 12 in the casing 11, and having an opening 14 at its top, in which a dispensing member or rod 15 is disposed. This dispensing member or rod 15 extends through an opening 16 in the base 12, so that it may be connected with a pump rod for operating a pump, to dispense the gasolene or other fluid which is to be sold.

Secured to the dispensing member or rod 15 there is a plate 17 having a plurality of vertical guideways 18 in which rack bars 19, 19^a, 19^b, 19^c and 19^d are disposed, the rack bar 19 being provided for dispensing a dollar's worth of gasolene when a dollar is inserted in the slot 20 shown in Fig. 1 of the drawings; the rack bar 19^a being provided for dispensing fifty cents' worth of gasolene when a fifty-cent piece is inserted in the slot 20^a; the rack bar 19^b being provided for dispensing twenty-five cents' worth of gasolene when a twenty-five-cent piece is inserted in the slot 20^b; the rack bar 19^c being provided for dispensing ten cents' worth of gasolene when a ten-cent piece is inserted in the slot 20^c, and the rack bar 19^d being provided for dispensing five cents' worth of gasolene when a five-cent piece is inserted in the slot 20^d. The teeth of the racks 19, 19^a, 19^b, 19^c, and 19^d are connected by gearing 21, 22, 23 and 24, so that when the rack bar 19 is raised or lowered as may be desired, with reference to the quantity of gasolene which is to be sold for one dollar, the rack bars 19, 19^a, 19^b, 19^c and 19^d will be raised or lowered, the gearing being such that when the rack bar 19 is raised one-quarter of the distance between its pin 28 and a horizontal bar 29, the rack bars 19^a, 19^b, 19^c and 19^d will be raised one-quarter of the distances between their pins 28 and the said horizontal bar 29, so that with any increase in the price of gasolene, the amount to be dispensed for fifty cents, twenty-five cents, ten cents, or five cents, will be regulated by the regulation of the rack bar 19 to determine the amount of gasolene to be dispensed for one dollar.

As a means for regulating the movement of the rack bar 19 relatively to the plate 17, I provide a transverse shaft 25 which is

geared to the teeth of the rack bar 19 for raising or lowering the rack bar, it being possible to rotate the shaft 25 as may be desired by means of the hand wheel 26; the 5 distance it is necessary to move the rack bar 19 by means of the hand wheel 26 and the shaft 25 being indicated by a dial 27. It will therefore be seen that when the dispensing member or rod 15 is raised with the 10 operation of the machine, it will carry up with it the plate 17, which will carry the rack bars, 19, 19^a, 19^b, 19^c and 19^d, having the pins 28, the said pins 28 being provided for tripping triggers which will shortly be 15 described, for throwing the operating mechanism into inoperative position.

When a twenty-five cent piece is inserted in the coin slot 20^b, it will travel along a chute 290 to a shoulder 30 on a rack bar 31, 20 the twenty-five cent piece being held against this shoulder by an arm 32 mounted on a disk 33 having gear teeth 34 at one side. This disk 33 is secured for moving with a lever 35, and when the twenty-five cent piece 25 is held against the shoulder 30 in the rack bar 31 by the said arm 32, and the lever 35 is pressed down, the arm 32 in connection with the twenty-five cent piece will raise the rack bar 31 far enough for its teeth 36 to be 30 positioned where they will be engaged by the teeth 34 at the side of the disk 33, and with the further rotation of the disk 33 by means of the lever 35, the teeth 34 and 36 will serve to raise the rack bar 31, which 35 travels in a guide 37, the rack bar 31 at its upper end 35 engaging an arm 39 secured to a shaft 55, from which another arm 41 extends, the arm being divided and being disposed in an annular groove 42 on a 40 clutch member 43 keyed to a shaft 44, in a manner well understood. This clutch member 43 is provided for engaging a companion clutch members 45 mounted for rotating with a pinion 46 which is in mesh 45 with rack teeth 47 on the dispensing member or rod 15. It will, therefore, be understood that when the rack bar 31 is raised by the means which have been described, it will move the clutch member 43 into engagement 50 with the clutch member 45 against the resiliency of the spring 48, so that the clutch member 45 and its pinion 46 may be rotated by means of a crank 49 and the shaft 44, and that with this rotation of the pinion 46, the 55 dispensing member or rod 15 will be raised to operate the pump.

As has been stated, the rack bars 19, 19^a, 19^b, 19^c, and 19^d, are provided to limit the movement of the dispensing member or rod 60 15, so that the amount of gasoline or other fluid dispensed at one time may be regulated with reference to the current price of gasoline and the denomination of the coin inserted in one of the coin slots. This is accomplished in the following manner: Each

of the rack bars 31 has a rearwardly extending wrist pin 50, to which is articulated a depending trigger 51, each of the triggers 51 being adapted to be disposed in guideways 52 in the horizontal bar 29. Each 70 trigger 51 moves upwardly with its rack bar 31, so that the trigger 51 may be pressed laterally by its spring 53 to a position where it will rest at its cut-in portion 54 on the horizontal bar 29. This will serve to hold 75 the rack bar 31 in its upward position after the disk 33 has been rotated to a point where its teeth 34 will leave the teeth 36 on the rack bar 31, and the rack bar 31 will be held upward as has been described until 80 the trigger 51 is moved against its spring 53 so that it may again move back to neutral position in its guideway 52 in the horizontal bar 29. The rack bars 19, 19^a, 19^b, 19^c and 19^d are moved upwardly with the 85 plate 17 which is secured to the dispensing member or rod 15, which have been described, and the position of the said rack bars 19, 19^a, 19^b, 19^c and 19^d is adjusted relatively to the plate 17, as has been described, 90 so that they will trip the triggers 51 at predetermined times, to permit the triggers 51 to fall in their guideways 52, thereby permitting the rack bars 31 to move downward, and, by the means which have been described, freeing the clutch member 43 from the clutch member 45, to disconnect the operating mechanism, so that further movement of the dispensing member or rod 15 is prevented, should the operator continue to 95 rotate the crank 49.

If a fifty-cent-piece is deposited in the coin slot 20^a, it will fall against the shoulder 30 on the rack bar 31^a, and be engaged by the arm 32 on the disk 33^a. When the 105 lever 35 is pressed down, this will raise the arm 39^a, which is secured to the shaft 55, thereby serving to move the arm 41 to throw the clutch member 43, in the manner which has been described. The operating mechanism is thrown into operative position by this means, and the operating mechanism is thrown out of operative position after fifty cents' worth of gasoline has been dispensed, by means of the pin 28 on the rack bar 19^a, 110 which will, by the means which have been described, move the trigger 51^a against the resiliency of its spring 53^a, so that the trigger 51^a will move down in its guideway 52 in the horizontal bar 29. The position of the pin 28 on the rack bar 19^a is such that it 115 will trip its trigger 51^a when the plate 17 has moved upwardly a distance which is one-half of the distance which the rack bar 19 with the plate 17 will move upwardly before the pin 28 on the rack bar 19 trips its trigger 51. Therefore, only one-half as much gasoline will be dispensed when a fifty-cent-piece is deposited in the coin slot 21^a as would be the case where a silver dollar 120

is deposited in the coin slot 20, and the machine operated. In the same way the plate 17 will move upwardly with the dispensing member or rod 15 one-half the distance that 5 the rack bar 19^a will move upwardly with the plate 17 and dispensing member or rod 15, before the pin 28 on the rack bar 19^b trips its trigger 51. The arrangement is the same with reference to the pins 28 on the 10 rack bars 19^c and 19^d, the pins 28 on each of the rack bars engaging an inclined surface 56 on a projecting member 57, on its trigger 51.

In Fig. 7 of the drawings, I show the 15 position of the disk 33 with its gear teeth 34, with reference to the rack bar 31 and its teeth 36, before a coin has been introduced in a coin slot. In Fig. 8, I show the relative position of the disk 33 and the rack 20 bar 31 when a coin has been introduced in the coin slot and the lever 35 has been pressed downward to raise the rack bar 31 to a position where the gear teeth 34 on the disk 33 are in mesh with the teeth 36 on the 25 rack bar 31. In Fig. 9 of the drawings, I show the relative position of the disk 33 and the rack bar 31 after the disk 33 has been rotated, carrying with it the arm 32 to a position where the coin is freed from the 30 arm 32 and the shoulder 30 of the rack bar 31. The disks 30, 30^a, 30^b, 30^c, and 30^d are all secured to a common shaft 58, which is operated by the lever 35 which has been described.

35 The horizontal bar 29 is secured to the frame 13 as well as the guide 37 and bearings 59 in which the shaft 58 is journaled. The shaft 44 is journaled in the bearing 60 in the casing 11, and also in the bearing 61, 40 mounted on the frame 13, the clutch member 45 being free to rotate on the shaft 44, and the clutch member 43 being keyed to the said shaft 44, in a manner well understood.

45 Springs 62 are secured to the coin chutes 290 and press against the arms 32 at one side, and springs 63 are secured to the disk 33 and press against the arms 32 at their other side, for holding the arms 32 yieldingly in position.

50 Having thus described my invention, what I claim as new and desire to secure by Letters Patent, is:

1. In a fluid vending machine, an operating member, a plate for moving with the 55 operating member, a plurality of rack bars movable on the plate, gears connecting the rack bars for moving the rack bars at different speeds, means for actuating the operating member, triggers mounted for moving in the paths of the rack bars to be operated thereby, and means adapted to be operated by the triggers for moving the first means to inoperative position.

2. In a fluid vending machine, an operating member, a plate for moving with 60

the operating member, a plurality of bars adjustable on the plate relatively to each other, means for actuating the operating member, triggers for moving in the paths of the bars, to be operated thereby, and 70 means adapted to be actuated by the triggers for moving the first means to inoperative position.

3. In a fluid vending machine, an operating member, a plurality of bars adjustable relatively to each other and mounted for moving with the operating member, means for actuating the operating member, and means adapted to be operated by a predetermined bar for moving the first means 80 to inoperative position.

4. In a fluid vending machine, an operating member, a plate for moving with the operating member, a plurality of rack bars movable on the plate, gears connecting the 85 rack bars for moving the rack bars at different speeds relatively to the plate, means for operating the operating member, and means adapted to be operated by a predetermined rack bar for moving the first means to inoperative position.

5. In a fluid vending machine, an operating member, a plate for moving with the operating member, a plurality of rack bars movable on the plate, gears connecting the 95 rack bars for moving the racks at different speeds relatively to the plate, means for actuating the operating member, means adapted to be operated by a predetermined rack bar for moving the first means to inoperative position, and means for moving one of the rack bars relatively to the plate.

6. In a fluid vending machine, an operating member, a plate for moving with the operating member, a plurality of rack bars 105 movable on the plate, gears connecting the rack bars for moving the rack bars at different speeds relatively to the plate, means for actuating the operating member, means adapted to be operated by a predetermined 110 rack bar for moving the first means to inoperative position, a dial, a third means for moving one of the rack bars relatively to the plate, a hand for the dial, and means operable by the third means for moving the hand 115 relatively to the dial.

7. In a fluid vending machine, a bar, a support for a trigger, a trigger adapted to rest on the support and provided with an inclined surface for engagement by a member on the bar to move the trigger off the support, and operating means adapted to be actuated by the trigger for moving said operating means into inoperative position.

8. In a fluid vending machine, an operating member, a bar for moving with the operating member, a support for a trigger, a trigger adapted to rest on the support, and provided with an inclined surface for engagement by a member on the bar to move 120

the trigger off of the support, means for actuating the operating member, a clutch member secured to the means, a companion clutch member for coöperating with the first clutch member, means for moving the companion clutch member into engagement with the first clutch member, and a second bar to which the trigger is secured and which engages the second means, for moving the companion clutch member into engagement with the first clutch member when the trigger rests on the support.

9. In a fluid vending machine, an operating member, a bar for moving with the operating member, a support for a trigger, a trigger adapted to rest on the support and provided with an inclined surface for engagement by a member on the bar to move the trigger off of the support, means for moving the trigger over the support when it is raised therebeyond, means for actuating the operating member, a clutch member secured to the means, a companion clutch member for coöperating with the first clutch member, means for moving the companion clutch member relatively to the first clutch member, resilient means for holding the second means with the companion clutch member away from the first clutch member, and a second bar to which the trigger is secured and which engages the second means for moving the companion clutch member into engagement with the first clutch member when the trigger rests on the support.

35 10. In a fluid vending machine, an operating member, means for actuating the operating member, a clutch member secured to the means for operating the latter, a companion clutch member, resilient means for moving the companion clutch member out of engagement with the first clutch member, a bar engaging the resilient means for moving the companion clutch member into engagement with the first clutch member, and means for holding the bar in operative position adapted to be actuated by the movement of the operating member beyond a predetermined point.

50 11. In a fluid vending machine, an operating member, means for actuating the operating member, a clutch member secured to the means for operating the latter, a companion clutch member, resilient means for moving the companion clutch member out of engagement with the first clutch member, a bar engaging the resilient means for moving the companion clutch member into engagement with the first clutch member, a support for a trigger, a trigger for resting on the support for holding the bar operatively in engagement with the resilient means, and means operable by the operating member for moving the trigger off of the support.

60 12. In a fluid vending machine, an oper-

ating member, means for actuating the operating member, a clutch member secured to the means for operating the latter, a companion clutch member, resilient means for moving the companion clutch member out of engagement with the first clutch member, a bar engaging the resilient means for moving the companion clutch member into engagement with the first clutch member, a support for a trigger, a trigger secured to the bar, the trigger resting on the support when the bar operatively engages the resilient means and being provided with an inclined surface, a bar for engaging the inclined surface on the trigger to move the trigger off of the support, and means connecting the operating member with the second bar, for operating the latter.

13. In a fluid vending machine, a rotatable disk having gear teeth at one side, a rack bar having gear teeth and a shoulder for receiving a coin, an arm on the disk for engaging the coin at the shoulder on the rack bar for pressing the coin against the shoulder when the disk is rotated to raise the bar to a position where the teeth on the disk will mesh with the teeth on the rack bar, so that with the further rotation of the disk the rack bar will be raised independently of the arm and the coin, an operating member, means for actuating the operating member, and means for moving the first means into operative position, adapted to be actuated by the rack bar when it is raised.

14. In a fluid dispensing machine, a rotatable disk having gear teeth at one side, a rack bar having gear teeth and a shoulder for receiving a coin, an arm on the disk for engaging the coin at the shoulder on the rack bar, for pressing the coin against the shoulder when the disk is rotated to raise the rack bar to a position where the teeth on the disk will mesh with the teeth on the rack bar, so that with the further rotation of the disk the rack bar will be raised by the said teeth, an operating member, means for actuating the operating member, means for moving the first means into operative position adapted to be operated by the rack bar when it is raised by the teeth, a bar, a trigger for resting on the bar and secured to the rack bar for holding the latter in raised position when the teeth on the disk are no longer in mesh with the teeth on the rack bar, and means connected with the member for moving the trigger off of the second bar when the dispensing member has moved to a predetermined point.

15. In a fluid dispensing machine, a rotatable disk having gear teeth at one side, a rack bar having gear teeth and a shoulder for receiving a coin, an arm on the disk for engaging the coin at the shoulder on the rack bar, for pressing the coin against the

- shoulder when the disk is rotated to raise the bar to a position where the teeth on the disk will mesh with the teeth on the rack bar, so that with the further rotation of the disk the rack bar will be raised by the teeth, an operating member, means for actuating the operating member, means for moving the first means into operative position and adapted to be actuated by the rack 10 bar when it is raised by the teeth, a second bar, a trigger for resting on the second bar and secured to the rack bar for holding the latter in raised position, the trigger having an inclined surface, a third bar for engaging the trigger at the inclined surface for moving the trigger off of the second bar, and means connecting the operating member with the third bar, for operating the latter.
- 20 16. In a fluid vending machine, a rotatable disk having gear teeth at one side, a rack bar having gear teeth and a shoulder for engaging a coin, an arm on the disk for engaging the coin at the shoulder on the 25 rack bar, for pressing the coin against the shoulder when the disk is rotated to raise the rack bar to a position where the teeth on the disk will mesh with the teeth on the rack bar, so that with the further rotation of the disk the rack bar will be raised by the teeth, an operating means, and means for actuating the operating means operable by the rack bar.
- 30 17. In a fluid vending machine, an operating member, means for actuating the operating member, a plate for moving with the operating member, a plurality of bars 35
- adjustable relatively to each other on the plate, for moving therewith, and means for disposal in the path of a predetermined bar 40 for moving the first means to inoperative position.
18. In a fluid vending machine, an operating member, means for actuating the operating member, a plurality of bars adjustable relatively to each other, and means for disposal in the path of a predetermined bar 45 for limiting the movement of the operating member.
19. In a fluid vending machine, an operating member, means for actuating the operating member, a plurality of rack bars, gearing connecting the rack bars for moving the rack bars at different speeds, and means for disposal in the path of a predetermined rack 50 55 bar for limiting the movement of the operating member.
20. In a fluid vending machine, an operating member, means for actuating the operating member, a plate for moving with the operating member, a plurality of rack bars 60 movably mounted on the plate, gearing connecting the rack bars for moving the rack bars at different speeds, and means for disposal in the path of a predetermined rack 65 bar for moving the first means to inoperative position.

In testimony whereof I have signed my name to this specification in the presence of two subscribing witnesses.

JASON McGREGOR CHANDLER.
